EDGE TRIMMING ATTACHMENT

Joseph Chudner, Brooklyn, N. Y.

Application September 22, 1933, Serial No. 690,613

6 Claims. (Cl. 112—122)

This invention relates to a device or attachment which may be used advantageously in conjunction with a sewing machine so that goods can be stitched and edge trimmed in one operation.

5 The principal object of the invention is the provision of a device or attachment of the indicated character to enable convenient adjustments to suit varieties of work, and which makes it possible for an operator to clearly view the work while operating the machine to secure accurate work with clean cut edges.

Another object of the invention is the provision of a device or attachment of the indicated character which will be simple, efficient and of substantial design.

The invention consists in the improvements as hereinafter described and claimed, and as illustrated by way of example in the accompanying drawings, in which—

20 Figure 1 is a plan view of the device or attachment operatively connected with portions of a sewing machine, and one of the parts being shown in section;

25 Figure 2 is a section taken on the line 2—2 of Figure 1;

Figure 3 is a plan view of the detachable unit of the device; and

Figure 4 is a section taken on the line 4—4 of Figure 3.

30 As stated, the device or attachment is used in conjunction with a sewing machine, and in the drawings there have been illustrated portions of the machine directly involved consisting of the bed 10, feed-lifting rock shaft 11 supported by suitable bearings, one of which is shown and designated 12; on the under side of the bed 10 at the front thereof; and a throat, feed and needle plate 13 which is detachably secured to the bed 10 by screws 14, the plate 13 being flush 40 with the upper surface of the bed 10.

The device or attachment includes a unit which is secured to the plate 13 so as to be removed with the plate 13 by removing the screws 14. The unit includes a part or block 15 which is secured to the plate 13 by screws 16 passing upwardly through the plate 13 into threading engagement with the part 15. This part or block 15 has a projection 17 over which the material or cloth to be stitched and trimmed rides. The part 50 15 also has spaced bearings 18. The unit also includes a trimming or shearing couple consisting of a knife, cutter or trimmer blade 19 and a bar 20 having a shearing or cutting edge 21 with which the blade 19 cooperates. The blade 19 is 55 secured to a member 22 on one end of a shaft 23

by a screw 24 and a pin 25. The screw 24 passes through the blade 19 and is in threading engagement with a tapped hole in the shaft 23. The pin 25 is carried by the member 22 and extends in a hole in the blade 19 to prevent the blade from 60 turning. The member 22 is rounded as at 26 so as to deflect the trimmed portion of the material or cloth, as shown most clearly in Figure 1, the cloth or material being shown in dot-and-dash lines and being designated 27. The shaft 23 is 65 supported by the bearings 18 and has axial and also rocking movement in said bearings. The bar 20 is held in place by the plate 13 and the part 15, and also a set screw 28, as shown most clearly in Figure 4. The part 15 has a groove 70 29 to receive one edge of the bar 20. The screw 28 is in threading engagement with the part 15 and bears on the bar 20. By loosening the screw 28, the bar 20 may be slid to various positions of adjustment in order to trim the material or cloth 75 at various distances with respect to the line of stitching indicated at 30. It will be apparent that the shearing line of the elements 19 and 20 will be adjacent the edge of the material or cloth being fed in the usual manner, and that this 80 shearing line will be parallel to the stitching line 30, as shown most clearly in Figure 1. Resilient means is employed to yieldingly hold the blade 19 against the cutting edge 21, to thus steady the blade 19 and keep it in proper shearing relation 85 with respect to the edge 21. The said resilient means consists of a strip 31 of spring steel, and this strip 31 is substantially of L-shape and has one end thereof secured to the part 15 by a screw 32, and its opposite end has a notch 33 therein so 90 that said end may be disposed against a shoulder 34 on the projecting end of the shaft 23 opposite that having the blade 19. The shaft 23 is grooved to provide the shoulder 34, and the reduced portion 35 of the shaft is disposed in the 95 notch 33, as shown most clearly in Figure 3. It will be apparent that the spring strip 31 constantly urges the shaft 23 axially in one direction to yieldingly hold the blade 19 against the cutting edge 21 of the bar 20. It will also be apparent 100 that when the screw 28 is loosened for the purpose of adjusting the bar 20, the blade 19 may be adjusted at the same time by reason of the fact that the shaft 23 may have axial movement, and also by reason of the resiliency of the spring 105 strip 31.

The blade 19 is caused to move or rock in a vertical plane with respect to the cutting edge 21 to produce the shearing or trimming action, in response to the operation of the rock shaft 11. 110

This is accomplished by the use of an arm 36 which is secured to the shaft 23 by a set screw 37. The arm 36 has an arbor or pivot 38 on its outer end disposed parallel to the shaft 23. A curved link 39 has its upper end pivotally and slidably connected with the pivot 38, and the lower end of the link 39 is pivotally connected as at 40 with one end of an arm 41 whose opposite end is secured to the shaft 11 by a set screw 42. It will now be apparent that the blade 19 will have a rocking motion imparted thereto in response to the rocking motion of the shaft 11, through the intervention of the shaft 23, arm 36, link 39, and the arm 41. It will be understood that the shaft 11 will be put in motion when the sewing machine is being operated in the usual manner for stitching the material or cloth. It will also be apparent that while the material or cloth is being stitched, an edge portion thereof 20 will be trimmed off in one and the same operation.

Attention is called to the fact that the sliding connection between the upper end of the link 39 and the pivot 38 enables adjustments to be made 25 to the cutting bar 20 and the blade 19 without detaching the arm 36 from the link 39; that the pivotal connection of the link 39 with the pivot 38 of arm 36 may be disengaged by first either detaching the blade 19, or by turning the shaft 30 23 so that the blade 19 will clear the bar 20, and then moving the shaft 23 axially to the right as viewed in Fig. 3; and that the unit comprising the parts shown in Figure 3 may be readily detached by merely removing the screws 14, when 35 it is desired to eliminate shearing or trimming of the work.

I claim:—

1. The combination with a sewing machine including a removable needle plate and a cloth feed 40 operating rock shaft; of a cloth trimming device carried by said plate, and means connected with said shaft and detachably connected with said device which operates the device in response to the rocking movement of the shaft.

45 2. In an edge trimming device, the combination of cooperative shearing elements mounted to position their shearing line adjacent the edge of the material traveling by, both of said elements being adjustable, means causing the adjustment of one of said elements as the other is being adjusted, and also to maintain the adjustment of the former in cooperative shearing 50 relation to the latter, said means including a rockable and slidably member on which said shearing element is mounted, and a resilient member constantly acting on said member; and means to rock said member which also allows

said adjustment to be made without requiring disconnection of said last means.

3. In an edge trimming device, the combination of cooperative shearing elements, a shaft mounted for axial and rocking movement, one 80 of said elements being secured to said shaft for movement therewith, a driven element for imparting rocking motion, an arm on said shaft, an arm on said driven element, and a link between said arms and having pivotal connection therewith, the pivotal connection of the link with the arm on said shaft being such that the link may be disengaged from said arm by moving the shaft first on its own axis and then moving it 85 axially a predetermined degree.

4. In an edge trimming device, the combination of cooperative shearing elements, a shaft mounted for axial and rocking movement, one 90 of said elements being secured to said shaft for movement therewith, a driven element for imparting rocking motion, an arm on said shaft, an arm on said driven element, a link between 95 said arms and having pivotal connection therewith, the pivotal connection of the link with the arm on said shaft being such that the link 100 may be disengaged from said arm by moving the shaft first on its own axis and then moving it axially a predetermined degree, and resilient means acting on said shaft to constantly urge it axially, so as to maintain the shearing element 105 thereon in cooperative relation to the other shearing element.

5. In an edge trimming attachment for a sewing machine, the combination of a needle plate, a bearing member fixedly secured to said plate, 110 a shaft supported by said bearing member for axial and rocking movement, a trimmer secured to said shaft to be operated thereby, resilient means secured to said bearing member and engageable with said shaft to constantly urge it 115 axially in one direction to yieldingly retain the trimmer in a proper trimming position, but allowing the shaft to rock, and means on the shaft for causing it to rock.

6. In an edge trimming device, the combination 120 of cooperative shearing elements, a shaft mounted for axial and rocking movement, one of said elements being secured to said shaft for movement therewith, a driven element for imparting rocking motion, an arm having a pivot 125 on said shaft, an arm on said driven element, and a link, one end of said link being pivotally and slidably connected with said pivot, and the other end of said link being pivotally connected with the arm on said driven element.

JOSEPH CHUDNER.
